US00D942471S

(12) **United States Design Patent** (10) Patent No.: **US D942,471 S**
 Kim et al. (45) Date of Patent: ** Feb. 1, 2022

(54) **DISPLAY SCREEN OR PORTION THEREOF INCLUDING A GRAPHICAL USER INTERFACE**

(71) Applicant: **SAMSUNG ELECTRONICS CO., LTD.**, Suwon-si (KR)

(72) Inventors: **Jimin Kim**, Mountain View, CA (US); **Jonathan P. Gaiser**, Mountain View, CA (US); **Anthony A. Shumskas**, Mountain View, CA (US); **Melinda Yang**, Mountain View, CA (US); **Jorge T. Furuya Mariche**, Mountain View, CA (US)

(73) Assignee: **SAMSUNG ELECTRONICS CO., LTD.**, Suwon-si (KR)

(**) Term: **15 Years**

(21) Appl. No.: **29/745,492**

(22) Filed: **Aug. 6, 2020**

Related U.S. Application Data

(62) Division of application No. 29/702,478, filed on Aug. 20, 2019, now Pat. No. Des. 892,826, which is a division of application No. 29/605,471, filed on May 26, 2017, now Pat. No. Des. 871,421.

(57) **CLAIM**

The ornamental design for a display screen or portion thereof including a graphical user interface, as shown and described.

DESCRIPTION

FIG. 1 is a front view of a first embodiment of the display screen or portion thereof including a graphical user interface according to our new design.

FIG. 2 is a front view of a second embodiment of the display screen or portion thereof including a graphical user interface according to our new design.

FIG. 3 shows the graphical user interface of the first embodiment; and,

FIG. 4 shows the graphical user interface of the second embodiment.

The broken lines showing a display screen or portion thereof and elements of the graphical user interface illustrate portions of the article, and form no part of the claimed design.

1 Claim, 4 Drawing Sheets
